UNITED STATES PATENT OFFICE.

ERNEST CHARLES REED, OF RAAMSDONK, NETHERLANDS.

NEEDLE-LUBRICATOR.

SPECIFICATION forming part of Letters Patent No. 758,473, dated April 26, 1904.

Application filed August 10, 1903. Serial No. 169,028. (No model.)

To all whom it may concern:

Be it known that I, ERNEST CHARLES REED, paper manufacturer, a subject of the King of Great Britain and Ireland, residing at Raamsdonk, North Brabant, in the Kingdom of the Netherlands, have invented certain new and useful Improvements in Needle-Lubricators, of which the following is a specification.

My invention relates to needle-lubricators—that is to say, lubricators in which a bottle or container for the lubricant is used together with a needle or rod passing through an outlet-passage from the bottle or container, the said passage being of a size to allow a proper quantity of lubricant to pass through it and around the needle or rod when the outer end of the needle or rod is in contact with a shaft or other moving part to be lubricated. In such lubricators grit and dirt present in the lubricant pass therewith into the passage from the bottle, and such grit and dirt as may remain in the said passage impede the proper action of the needle or rod, while grit and dirt which pass out therefrom cause heating of the bearings or surfaces to the lubrication of which the lubricator is applied.

The object of my invention is to overcome these objections and to provide a needle-lubricator in which grit and dirt that may be in the lubricant in the bottle or container are prevented from finding their way to the passage through the stopper.

According to my invention I support within the bottle or container a mantle or tube of textile fabric, and arranged in such a way as to allow the lubricant to pass through the said mantle or tube, but to intercept grit and dirt, while leaving a space inside the mantle or tube of filtering material and its support to allow the needle or rod to move freely within the bottle or container.

I will describe, with reference to the accompanying drawings, a lubricator in accordance with my invention, premising that I do not limit myself to the precise details shown therein, as they can be considerably varied without departing from the nature of my invention.

Figure 1 is an elevation, and Fig. 2 is a vertical section, of a lubricator constructed in ac-

cordance with my invention. Fig. 3 is an elevation of the mantle or tube of filtering material upon its support, and Fig. 4 is a plan of the inner end of the stopper of the bottle or container.

55

A is the bottle containing the lubricant, and B is the stopper, with a passage through it lined or bushed, as usual, with the metal tube b. C is the needle or rod, with an enlarged inner end c. These parts are or may be the same as in ordinary needle-lubricators. The following are the additions in accordance with my invention:

D is a perforated tubular support closed at its upper end, its other end being fitted into a circular recess b² made in the stopper B concentrically with the tube b. Over the whole of the perforated part of the support D is passed a mantle or tube E of filtering material, which will allow of the passage of the lubricant, but intercept grit and dirt, a very suitable and convenient form of material being knitted cotton resembling a circular lamp-wick. The support D and mantle or tube E completely separate the space in which the needle or rod C moves from the space into which the lubricant is introduced into the bottle or container, and no lubricant that has not passed through the mantle or tube of filtering material E can gain access to the space within the said mantle or tube of filtering material and its support and to the outlet-tube b, and consequently no grit or dirt can get into the said tube b or pass to the surfaces being lubricated, and therefore the needle C always works freely and there is no danger of grit or dirt which may be in the main space in the bottle or container passing to the bearings or the like and causing overheating thereof. The mantle or tube of filtering material E preferably has its edges gummed to make them smooth, and the said mantle or tube E (and also its support D when required) can be easily removed and cleansed or a clean mantle or tube put in place.

90

It will be evident that the details described can be considerably varied without departing from the nature of my invention. For example, the support D may be made of wire-gauze or of slitted material or the like or of

95

100

bars or of a coiled wire, and the inner end may be open and covered by an end formed on the mantle or tube of filtering material or be closed by a cork or otherwise. If desired, 5 the lower end of the support D can be screwed into the circular recess b.

I am aware that lubricators have been provided with filtering material; but this has been done by placing loose material, such as 10 "hemp-waste," in the passage from the bottle or container, and such material so applied has not been efficient in excluding dirt, nor has it been arranged so as to allow a space for the needle or rod to move in, and therefore 15 no needle or rod has been used in such lubricators, and they have been without the control which it is the function of the needle or rod to exercise during the working of the machinery, and the passage for lubricant has 20 been always open, and lubricant has wastefully escaped when the machinery is at rest;

but in the arrangement according to my invention all the advantages of needle-lubricators are retained, while there is secured the additional advantage of preventing access of 25 grit and dirt to the tube b and to the surfaces being lubricated.

I claim as my invention—

A needle-lubricator, comprising a container, a stopper; a central tubular opening there- 30 through, a needle passing through said opening into the container, a perforated support surrounding said needle, and a filtering material of textile fabric covering the perforated support and separating the needle from the 35 container, substantially as described.

In testimony whereof I affix my signature in the presence of two witnesses.

ERNEST CHARLES REED.
